PORTABLE LIQUID OXYGEN UNIT

John A. Weaver, Detroit, Mich.

Application December 11, 1945, Serial No. 634,329

11 Claims. (Cl. 62—1)

(Granted under the act of March 3, 1883, as
amended April 30, 1928; 370 O. G. 757)

1

The invention described herein may be manufactured and used by or for the Government for governmental purposes without payment to me of any royalty thereon.

This invention relates to a portable liquid oxygen unit, having special reference to a small compact unit which may, if desired, be carried about on the person of the user to supply him with gas phase oxygen for a period of several hours.

An object of this invention is to provide a device of this character having a liquid oxygen storage receptacle suspended within a vacuum jacketed container, and means to intermittently transfer a small quantity of the liquid oxygen to an uninsulated enclosure to thereby subject it to atmospheric heat to convert it into gas phase oxygen.

Another object is to so construct and arrange the device that the recurrence of the conversion period is automatically responsive to the volume of gas phase oxygen being used.

Another object is to gimbally suspend the liquid oxygen storage receptacle within the vacuum jacketed container in such a manner that the liquid phase inlet and the gas phase outlet of the receptacle will always be respectively at the bottom and the top thereof with respect to the gravity axis regardless of the position of the housing and the other elements of the device.

Another object is to provide gauge means whereby the amount of liquid oxygen remaining in the device may be read directly at all times.

Other objects and advantages will become apparent from a consideration of the description taken in conjunction with the drawings, wherein:

Fig. 1 is a vertical axial sectional view of a device which embodies the principles of my invention.

Fig. 2 is an enlarged detail sectional view of the pressure regulating valve of my device in the open or unactuated position.

Fig. 3 shows the valve of Fig. 2 in the closed or actuated position.

Fig. 4 is an enlarged detail elevational view, partly in section, of the gauge for indicating the volume of liquid oxygen remaining at any time.

Like reference characters refer to like parts throughout the several views.

The several elements of my improved device are assembled and supported within a more or less cylindrical protective housing 10 which is open to the atmosphere at the bottom as at 12, the opening being covered by a screen 14 held on by screws 16. At one end the housing has a centrally disposed hub 18 through which the device is filled

2

with liquid oxygen and at the other end another hub 20 is provided for attachment of an oxygen mask through which oxygen is taken by the user after it has been converted to a gaseous state.

Centrally disposed within the housing 10 is a jacket 22 having a dome 24 at the top from which the jacket is supported in the housing by a universal joint 26. A washer like disc 28 is carried by the dome 24, and a ring 30 carried by the housing 10 surrounds the washer loosely, leaving only a very slight swinging movement of the jacket 22 on the universal joint 26. The ring 30 has a shoulder 32 and the disc 28 may preferably just touch this shoulder when the unit contains no liquid oxygen. The radius of the disc 28 should be equal to the distance from the disc to the center of the jacket 22. The purpose of thus limiting the swinging movement of the jacket 22 on the universal joint 26 will hereinafter appear.

Within the jacket 22 is a spherical container 34 which is spaced apart from the jacket by bridges 36 which are preferably of low heat conductivity, leaving a jacketed space 38 between the container 34 and jacket 22 which extends also up into the dome 24. The jacketed space 38 is evacuated and sealed whereby the container 34 is heat insulated.

Gimbalily supported within the container 34 by means of a gimbal ring 40 is a spherical receptacle 42 which is rotatable on an axis which is normally horizontal, as shown, by reason of the pivot bearings 44 and 46 of the receptacle, which have rotative bearing in the ring, the ring 40 being in turn rotatable on an axis which is normally vertical, by reason of the pivot bearings 48 and 50 of the ring which have rotative bearing in the container 34.

A weight 52 is fixed in the bottom of the receptacle, and a liquid phase orifice 54 extends through the weight and through the wall of the receptacle for connecting the inside of the receptacle to the space 56 between the receptacle and the container 34 within which the gimbal ring 40 rotates on its pivot bearings 48—50. A length of tubing 58 is bent to lie along the inside of the receptacle 42 to which it may be secured by any suitable means, the tube being constructed and positioned so that the upper or gas phase opening 60 is at top center when the liquid phase orifice 54 is at the bottom, the other end of the tube being bent laterally so as to extend through the pivot bearing 46. Perforated baffles 62 and 64 are fast in the top and bottom respectively of the receptacle 42 and are concentrically posi-

tioned with respect to the opening 86 and the orifice 54.

The gimbal ring 40 is provided with a duct 66 which connects the pivot bearing 46 to the pivot bearing 50. Ring 40 may be made of flattened tubing bent to circular form in which case the duct 66 may extend throughout the entire circumference. The space at the upper end of the bearing 50 is connected by a tube 68 to a relief valve 70, the tube 68 making at least one turn in the evacuated space 38 before connecting with the valve. Valve 70 is adjusted to maintain a pressure of 40 p. s. i., this selected pressure value being by way of example only.

A filler tube 72 extends from the filler hub 18 through the wall of the jacket 22 at 74 at which point it is sealed, then through the evacuated space 38 to a check valve 76. That portion of the filler tube 72 which is outside the jacket 22 is made flexible as at 78, while that portion within the jacket may be flattened as at 80 in order that it may occupy less space.

From the check valve 76, a branch tube 82 makes at least one turn before entering the container 34 at 84, and a second branch 86 goes to the inlet of the automatic pressure responsive valve 88. Valve 88 discharges into a warming coil 90, the turns of which are preferably laid on the outside of the jacket 22 and may be soldered or similarly secured thereto. The coil 90 discharges through the tube 88, part of which is flexible as at 91, into the regulator 82 which may be a diluter demand regulator of conventional design or similar device. A relief valve 94 prevents the pressure within the coil 90 rising above a predetermined value which may preferably be about 60 p. s. i. A conventional flow meter 96 may be provided to indicate the rate at which gas phase oxygen is being drawn from the demand regulator.

The automatic pressure responsive switch, broadly designated by the numeral 88, comprises an internally threaded valve body 98 within which a flanged valve seat member 100 is held by an externally threaded casing 102. A metal bellows 104 within the casing 102 has one end sealed to a washer 106 and the other end to a flanged hub 108, the washer being clamped between the end of the casing 102 and the flange of the valve seat member 100 and the flanged hub 108 being slideable axially within the casing 102. A valve head 110 has its stem 112 threadedly secured in the hub 108, a spring 114 contained in a recess 116 in the valve seat member 100 being provided to urge the valve head 110 on to its seat as seen in Fig. 3. An outlet passageway 118 extends laterally from the recess 116 for connection to the warming coil 90, whereby the space within the coil 90 is in communication with the inside of the bellows 104 and the pressure within the bellows therefore acts in conjunction with the spring 114 to maintain the valve 110 in closed position. The space 119 around the valve head 110 is in communication with the branch tube 86 whereby, when the valve head 110 is off its seat the branch tube 86 will be in direct communication with the warming coil 90. The space 120 within the casing 102 outside the metal bellows 104, and the space 122 at the end of the flanged hub 108, are vented to the atmosphere. A valve opening spring 124 acts against the end of the flanged hub 108 to urge the valve head 110 to the open position seen in Fig. 2. A cup-shaped nut 126 is externally threaded to engage internal threads in the casing 102 for adjusting the valve opening

spring 124. For illustrative purposes only it may be assumed that the nut 126 is so adjusted as to cause the valve head 110 to rise from its seat when the pressure within the warming coil 90 and passageway 118 drops to 30 p. s. i.

The mechanism shown in Fig. 4 for visual indication of the volume of liquid phase oxygen remaining at any time in the device, is broadly designated by the numeral 128 and is in the form of a spring weighing scale with the indicating means preferably graduated in litres and so arranged that the correct volume will be indicated in any position of the device not more than ninety degrees from the upright position.

The operative portion of the volume indicating mechanism 128 is contained within a case 130 integral with or attached to the top of the housing 10. An inverted cup 132 is rotatable on an antifriction bearing 134 in the bottom of the case 130, and carries a pointer 136 which may cooperate with a circular graduation on the underside of the glass 138 or on the top of the web 140 as desired.

Extending upwardly from the upper member 23 of the universal joint 26 is an operating stem 142 having at its upper end a flange 144 which rests on the top of a spring 146, the lower end of the spring resting on the bottom of the case 130. A shoulder 148 on the stem limits vertical travel 30 of the stem by contact with the bottom of the case.

In order that a vertical movement of the universal joint 26, due to a change in volume of the liquid phase oxygen within the container 34 and 35 parts associated therewith, may produce a rotary movement of the cup 132 and pointer 136, a helical slot 150 is cut through the side wall of the cup, and a pin 152 has the inner end fast in the flange 144 and the main body of the pin in the slot 150. Since the jacket 22, dome 24 and 40 contained parts cannot rotate materially due to the connections 78 and 91, the cup and pointer are rotated by vertical movement of the stem 142. A hairspring 154 is provided to minimize 45 backlash of the cup 132, one end being attached to the bearing member 134 and the other to the cup. The spring 146 should preferably be such that the washer 28 just touches the shoulder 32 when the device is empty and the shoulder 148 just touches the bottom of the cup 130 when the device is full. The spiral groove 150 may then be cut so as to make one complete turn when the spring 146 is compressed this amount.

The operation of the unit shown is substantially 55 as follows:

Liquid oxygen under a pressure of approximately 65 p. s. i. is brought from a source of supply through an insulated metal hose and disconnect attachment (not shown) through the 60 hub 18 and tubing 72, 78, and 80, through the check valve 76. Since the pressure responsive valve 88 is normally open when the device is empty, some liquid phase oxygen will pass through the tube 86 and valve 88 into the warming coil 90, which, being exposed to atmospheric 65 heat, will generate enough pressure in a matter of several seconds to close the valve 88.

When the pressure responsive valve 88 is closed, 70 fluid will thereafter flow only through the tube 82 and into the container 34 at 84, pass around the gimbal ring 40 and through the orifice 54 into the receptacle 42. Air or gas left in the receptacle 42 when it was not in use may pass out through the opening 60, tube 58, gimbal ring duct 66, out 75 through the pivot bearing 50 and tube 68 and the

relief valve 70. Since the relief valve 70 is set at 40 p. s. i. and the source of supply is at a pressure of 65 p. s. i., the relief valve will open and allow the air and gas to escape as soon as the pressure within the device exceeds 40 p. s. i. When the gauge 128 indicates that the device is properly filled, the source of supply may be disconnected from the hub 18 and a cap screwed thereover. The check valve 76 will hold the pressure until the hub has been capped.

Thereafter when the demand regulator 92 has drawn enough gas phase oxygen from the warming coil 90 to reduce the pressure within the warming coil to slightly less than 30 p. s. i., pressure responsive valve 88 will be opened slightly by the spring 134, and liquid phase oxygen will flow downward through the orifice 54 into the gimbal ring space 86 between the receptacle 42 and the container 34, out at 84 into the tube 82, through the valve inlet opening 80 and valve 88, and through the outlet opening 118 into the warming coil 90.

As soon as a relatively small portion of the liquid phase oxygen which has passed into the warming coil 90 is converted into gas phase oxygen, the pressure in the warming coil will have risen to 30 p. s. i., thereby closing the valve 88. The valve 88 may close, however, before all of the liquid phase oxygen in the warming coil has been converted, and if the conversion of the remainder of the oxygen raises the pressure in the warming coil to a value higher than the 60 p. s. i. at which the relief valve 94 is set, some gas phase oxygen will be lost through the valve.

It may therefore be desirable to so adjust the valve 88 by means of the screw 126 as to provide a valve closing pressure which will close the valve 88 before enough liquid phase oxygen has passed into the warming coil to raise the pressure therein above the value at which the relief valve 94 is set.

It is noted that all parts of the passageway which connects the opening 80 at the top of the receptacle 42 to the relief valve 70 are contained within the evacuated space, the normal conversion rate being therefore quite small. Since none of the gas phase oxygen within this passageway and within the upper portion of the receptacle has any outlet to the warming coil, it may be desirable that the conversion rate within the receptacle and its passageway be such that in a given period of time the increase in volume of gas phase oxygen be but very slightly more than enough to replace the liquid phase oxygen which has been received by the warming coil in that period, in which case the gas phase oxygen which will be lost through the relief valve 70 will be kept at a minimum.

It will be seen that the arrangement of the unit is such that if it is turned on the axis of the hubs 18 and 20, say ninety degrees from the vertical position of Fig. 1, the gimbal ring 40 will be in a horizontal instead of a vertical plane, but the weight 52 will rotate the receptacle 42 through ninety degrees to maintain the receptacle in the upright position shown.

On the other hand, if the unit is stood on end, say with the hub 20 downward, the weight 52 will coincidentally turn the gimbal ring 40 ninety degrees on the axis of the bearings 48 and 50 and turn the receptacle 42 ninety degrees on the axis of its bearings 44 and 46. Obviously the weight 52 will always be at the bottom and on the gravity axis.

In either of the positions above given as illustrations, the gauge 128 will continue to read cor-

rectly because in those positions the center of gravity of the jacket 22 and its contents will be in substantially the same horizontal plane as the universal joint 26, and the washer 28, resting on the shoulder 32 will form a fulcrum through which the force of gravity, acting downward at the center of the jacket will produce an equal force acting horizontally on the universal joint 26.

Having described an embodiment of my invention wherein the objects set forth are attained, I claim:

1. In a portable unit for storing liquid phase oxygen and controlling its conversion into gas phase oxygen, a heat insulated oxygen containing means, a relief valve, a passageway connecting the upper portion of said oxygen containing means to said relief valve, a pressure responsive valve having an inlet and an outlet opening, a passageway connecting the lower portion of said oxygen containing means to said inlet opening, a warming coil outside said oxygen containing means having one end connected to said outlet opening and the other end connected to a demand regulator, said pressure responsive valve being closable by a predetermined rise in pressure in said warming coil, and a second relief valve connected into said warming coil.

2. The unit defined in claim 1 wherein the second relief valve is set at a materially higher pressure than the first.

3. The unit defined in claim 1 with a housing surrounding the oxygen containing means, a spring weighing scale in the top of the housing supporting said oxygen containing means, and indicating means on said scale to show the amount of oxygen contained in said oxygen containing means.

4. In a portable unit for storing liquid phase oxygen and controlling its conversion into gas phase oxygen, a jacket, a container in said jacket with an evacuated chamber between, a gimbal ring pivotally supported in said container, a receptacle pivotally supported in said gimbal ring at points ninety degrees removed from the points where the gimbal ring is pivotally supported, and having an orifice in the bottom which opens into the gimbal space, weight means carried by said receptacle so placed as to maintain said orifice in its bottom position, a relief valve, a passageway connecting the top of said receptacle to said relief valve, a pressure responsive valve having an inlet and an outlet opening with means responsive to a drop in pressure in the outlet opening to open said valve, conduit means connecting the gimbal space to the said inlet opening, a warming coil outside said jacket having one end connected to said outlet opening and the other end connected to a demand regulator, and a second relief valve connected into said warming coil.

5. The unit defined in claim 4 wherein the said passageway extends from the inside of the receptacle at the top, to and through a pivot bearing of the receptacle, through a duct formed in the gimbal ring, out through the gimbal ring pivot bearing, and, by way of a conduit means, to the relief valve.

6. The unit defined in claim 4 with a housing surrounding the jacket, a weighing scale carried on said housing, a universal joint connecting said jacket to said weighing scale, a disc surrounding and secured to said jacket near said universal joint, a ring carried by said housing loosely surrounding said disc, and a shoulder in said ring positioned just above said disc when said unit is empty of liquid oxygen.

7. The unit defined in claim 4 with perforated conical baffles concentrically disposed over the opening in the top of the receptacle and the orifice in the bottom of the receptacle.

8. In a portable unit for storing liquid phase oxygen and controlling its conversion into gas phase oxygen, a heat insulated container, a relief valve having its inlet opening connected to the upper portion of said container and means operative at a preselected pressure to connect its discharge opening to the atmosphere, a pressure responsive valve having its inlet opening connected to the lower portion of said container and means responsive to a preselected pressure in its discharge opening to connect its inlet opening to its discharge opening, a warming coil connecting the discharge opening of the pressure responsive valve to a demand regulator, and a second relief valve having its inlet opening connected to the warming coil, and means operative at a preselected pressure to connect its discharge opening to the atmosphere.

9. The unit defined in claim 1 wherein the first relief valve is set to become operative at a mate-

rially higher pressure than the pressure responsive valve.

10. The unit defined in claim 1 wherein there are two stages of pressure, the higher stage governed by the setting of the first relief valve and the lower stage determined by the setting of the pressure responsive valve.

11. The unit defined in claim 1 wherein the pressure responsive valve is interposed between the higher stage of pressure in the container and the lower stage of pressure in the warming coil, and opens only when the pressure in the warming coil falls below the pressure in the container.

JOHN A. WEAVER.
